PROCESS FOR THE OXIDATION OF ORGANIC COMPOUNDS

Albyn William Norman Brown, Colin Bertie Cotterill, Fred Dean, and Gordon Howard Whitfield, all of Norton-on-Tees, England, assignors to Imperial Chemical Industries Limited, London, England, a corporation of Great Britain
No Drawing. Filed Oct. 28, 1957, Ser. No. 692,534
Claims priority, application Great Britain Nov. 21, 1956
4 Claims. (Cl. 260—524)

This invention relates to the oxidation of organic compounds.

According to the invention there is provided a process for the oxidation of organic compounds in the liquid phase by means of molecular oxygen or ozone characterised in that the oxidation is conducted with condensation of the overhead vapours, separation of water from the condensate, and reflux, under such conditions that the composition of the vapour over the liquid is in each stage of the oxidation outside the explosive range of compositions. Desired product can be recovered from the reaction product, for example by distillation.

The oxidation may be conducted in a single stage or in several stages. Moreover, the process may be operated batchwise or continuously. It is desirable that cooling be provided in the process, for example by means of the latent heat of vaporization of a reactant or reactants or of an inert solvent, or by the use of a coil through which fluid is circulated, or by external heat transfer means. The last mentioned is especially important when the reaction mixture under the oxidation conditions affords little self-cooling by evaporation of some of its components. The oxidation zone is preferably furnished with external heat transfer means, for example a jacket containing a liquid, for example water, boiling under pressure, and an associated condenser; the starting material is introduced near the top, and the oxidising gas near the bottom of the reaction zone; and the product is taken off at or near the bottom thereof. Preferably, also, the uncondensed vapours from the condenser are scrubbed with a liquid for recovery of residual starting material they contain.

In processes comprising several stages of oxidation each of the stages may be furnished with the auxiliaries just described. Further, in processes comprising more than one stage any or all of the stages may comprise two or more sub-stages each similarly conducted.

Where there are several oxidation zones distillation columns are preferably provided between them and can be run either, (i) to yield as overheads unoxidised starting materials and intermediate oxidation products for return to the prior oxidation stage, and as bottoms oxidation products for feeding to the next oxidation stage; or (ii) to yield as overheads unoxidised starting materials for return to the prior oxidation step and as bottoms intermediate and final oxidation products for feeding to the next oxidation step.

The process can be operated firstly under such conditions that the concentration of organic compounds in the vapour over the liquid is below that corresponding to the lower explosive limit. According to this method of operation it may be arranged that the vapour in equilibrium with the liquid in the oxidation reactor has a concentration of organic compounds below that corresponding to the lower explosive limits; or to operate with a liquid, the equilibrium vapour of which would lie within the explosive limits, but to bring the composition of the vapour below the lower explosive limit by introducing sufficient incombustible, inert diluent into the liquid or into the space above the liquid in the reaction zone.

2

Suitable incombustible inert diluents are, for example, nitrogen, carbon monoxide and steam.

The process can be operated secondly under such conditions that the concentration of organic compounds in the vapour over the liquid is above that corresponding to the upper explosive limit. According to this method of operation it may be arranged that the vapour in equilibrium with the liquid in the oxidation reactor has a concentration of organic compounds above that corresponding to the upper explosive limit, or to operate with a liquid of which the equilibrium vapour would lie within the explosive limits but to bring the composition of the vapour above the upper explosive limit by introducing sufficient volatile organic liquid either into the liquid or into the space above the liquid, so that in result the concentration of organic compounds in the actual vapour above the liquid is above that corresponding to the upper explosive limit. Sometimes this method of operation can be conducted by increasing the rate of boiling. It is often convenient to introduce the volatile organic liquid as a stream of vapour above the liquid. Suitable organic liquids are, for example, benzene, acetic and propionic acids, halogenated benzenes, e.g., chlorobenzene and ortho-dichlorobenzene, and fully halogenated aliphatic hydrocarbons such as carbon tetrachloride.

Another advantage of using such volatile organic liquids is that they function also to remove water formed in the reaction either as azeotrope, or by direct contribution of partial pressure. This water can be removed, for example, by means of a separator such as a Dean and Stark decanter situated in the exit line from the still of the reactor.

When operating so that the vapour over the liquid has a concentration of organic compounds above the upper explosive limit, it is advantageous to circulate the vapour in a closed system comprising a condenser and a purge line: the condensed starting material, and volatile solvent if one is used, are recycled to the oxidation step and the gas is purged. A similar procedure may be adopted, when a gaseous inert diluent is used, the condensed starting material being returned to the oxidation step and also some of the inert gas if this is economically justifiable.

It is an important feature of the invention that the oxidising gas be distributed highly efficiently in the reaction mixture: this applies especially when operating above the upper explosive limit. Suitable distributors are, for example, rapidly rotating gas mixers, e.g., a cruciform stirrer, high efficiency atomisers, turbulent jets, or sinter glass: of these the first two are preferred. By using such distributors the oxygen content of the vapour above the liquid can be kept to a minimum.

Increase in total pressure most frequently favours high utilization of oxygen and high reaction velocity in the reaction stages.

Most frequently in continuous operation counter-current flow of liquid and oxidising gas is preferred because then the highest concentration of oxidising gas is brought into contact with the material containing most oxidation product. However, if desired, co-current flow of liquid and oxidising gas may be used.

In many oxidations it is preferred to use substantially pure oxygen as the oxidising gas, because the over-all velocity of the reaction is largely determined by the rate of diffusion of the gas. It is then particularly important that a highly efficient gas distributor be used, as already described. However, in fast oxidation processes, or when the solubility of oxygen in the liquid is high, air or oxygen diluted with inert gases may conveniently be used. If substantially pure oxygen is used for these oxidations it is economic to recycle the exit gas stream from the oxidation reactor after removing oxides of carbon, for

example with aqueous alkali; by water extraction, or aqueous solutions.

It is an important feature of the present invention to operate the process outside the explosive range of compositions. These limits may be determined for a given mixture by the method described at pages 9 and 10 of Bulletin 503 of the U.S.A. Bureau of Mines, entitled, "Limits of Flammability of Gases and Vapours." The term "limits of flammability" normally refers to ignition at atmospheric pressure. Where ignition occurs in a closed system ignition is of the nature of an explosion and thus determination of the flammability limit is a sufficient index of the explosive limits (see, for example, "Principles of Chemical Engineering," by Walker, Lewis and Mc-Adams (McGraw-Hill), Second Edition, Seventh Impression, page 206, second paragraph).

For less volatile liquids the correct mixture to be tested can be prepared by passing a stream of the oxidising gas through a series of towers each containing an adsorbent such as kieselguhr loaded with the organic liquid. The towers are maintained at that temperature which yields a mixture with a partial pressure of organic compound corresponding to that which will be present in the reactor of the oxidation process. Care is taken to avoid condensation before feeding the mixture to the explosion tube by providing suitable heating means. The temperature in the explosion tube can be varied to correspond to the actual temperature in the oxidation process by providing the explosion tube with an external heating coil.

As discussed at page 3 of Bulletin 503, pressure has some modifying effect on the explosive limits and this must be borne in mind and due allowance made for it when the oxidation process is operated at superatmospheric pressure. For practical operation it is sufficient to make a determination of the concentrations of an organic compound or mixture of compounds corresponding to the lower and upper explosive limits by the methods above referred to, and then to arrange the operating conditions of the process so that the concentration is well outside these limits. Thus it may be necessary to work 1% or 2% or even further outside the explosive limits, but the width of tolerance necessary is a matter well within the skill of the qualified technical chemist. In many cases the question simply is: will a given mixture explode or not? A test made as above described will quickly decide this.

In those stages of the process where operation is above the upper explosive limit of the vapour, the concentration of the organic compound will very often after condensation, which is a necessary step, fall within the explosive range. This may happen, due to inefficiency of condensation, even when the equilibrium mixture of the gas and organic compound would not normally be explosive at the temperature in the condenser. It is therefore preferred to make provision for the admission of sufficient inert diluent, e.g., nitrogen, carbon dioxide or other inert gas, in close proximity to the potential hazard in order to eliminate it, for example in the exit gas line after the condenser.

According to another method of operation, which is continuous, the ozone, oxygen or oxygen-containing gas, is brought into contact with the organic compound in the liquid phase under such conditions that the concentration of organic compounds in the vapour above the liquid is greater than corresponds to the upper explosive limit, at least part of the oxidised liquid is taken off continuously and fed to a separating column; the overhead from this comprising the starting material is recycled to the reactor and the bottoms comprising intermediate and final oxidation products are fed to a second reactor provided with a condenser, reflux and decanter, in which they are brought into contact with air or oxygen or ozone, run under such conditions that the concentration of organic compounds in the vapour over the liquid is less than that corresponding to the lower explosive limit. The vapour from the second reactor emerging from the condenser may be sub-

jected in the exit gas line to further cooling or scrubbing for recovery of valuable residual compounds, if this is economic. As an alternative to the above procedure one or all of the intermediate products may be returned as overheads from the column to the first stage for oxidation there. In this process it is sometimes desirable to have present in the stage operated above the upper explosive limit, a more volatile combustible oxidation-stable solvent as already described.

In another form of the invention, which is continuous, the ozone, oxygen or oxygen-containing gas, is brought into contact with the organic compound in the liquid phase and partial oxidation is effected under such conditions that the concentration of organic compounds in the vapour above the liquid is greater than the upper explosive limits, at least a portion of the liquid mixture is withdrawn continuously to a second reactor in which the oxidation is continued and the composition of the vapour above the liquid is controlled outside the explosive limits by circulating it together with an inert in a closed system including a condenser and a purge line, and the liquid product from the second reactor is introduced into a third reactor in which it is reacted with oxygen or air under such conditions that the concentration of organic compound in the vapour is below the explosive limit. Both reactors are provided with reflux stills and with Dean and Stark decanters in the exit lines.

According to another continuous method applicable to some compounds it is possible to operate a two stage oxidation using two reactors in the first of which the concentration of the organic compound in the vapour above the liquid is above the explosive limit and in the second of which the liquid product from the first stage is oxidised under conditions such that the concentration of the organic compound above the liquid is below the explosive limit, each reactor being fitted with a reflux column provided with a Dean and Stark decanter in the exit line. Then the second stage is preferably operated at a higher total pressure.

The process can also be operated by distributing the organic compound to be oxidised in the oxidising gas by means of a packed tower or an atomizer nozzle, so that the liquid forms films.

The process is of especial value in relation to the oxidation of organic compounds in the liquid phase by means of ozone or molecular oxygen in the presence of a catalyst comprising a metal of variable valence, e.g., manganese and/or cobalt and bromine, commonly under superatmospheric pressure.

Example 1

60 grams of ortho-xylene dissolved in 120 grams of molten benzoic acid and containing as catalyst 0.33 gram of $MnBr_2 \cdot 4H_2O$ and 0.19 gram of $CoBr_2 \cdot 6H_2O$ was oxidized in the liquid phase at $150^\circ C$. and atmospheric pressure by passing oxygen into it at a rate of 24 litres per hour through a high speed cruciform stirrer. Simultaneously 300 litres per hour of steam measured at $100^\circ C$. was blown over the liquid reaction surface. The vessel was provided with a reflux column and a Dean and Stark decanter in the gas exit line, and water was condensed from the exit gas stream. Analysis of the uncondensed gas showed an average oxygen absorption of approximately 3 litres per hour. 20 mls. of benzene were included in the reaction mixture with the object of avoiding blocking of the decanter by benzoic acid carried over, and this, with any unconverted ortho-xylene was continuously returned to the oxidation vessel by overflow.

After 14 hours running 27 mls. of water was added to the reaction mixture, and the latter was hydrolysed for $1\frac{1}{2}$ hours under reflux. On filtering the molten mixture, boiling the precipitate with ether, refiltering and drying the precipitate, there was obtained 14.7 grams of phthalic acid (99.2% pure).

Example 2

40 grams of para-xylene dissolved in 200 grams of propionic acid was treated with well dispersed oxygen at 137° C. under reflux in the presence as catalyst of 0.33 gram of MnBr₂.4H₂O and 0.19 gram of CoBr₂.6H₂O, using an oxygen rate of 12 litres per hour. The boil-up rate was maintained at approximately 2 gram moles per hour of propionic acid to ensure that the concentration of the latter in the vapour was such that the vapour was above the higher inflammability limit. The vapours from the reaction vessel passed through a packed reflux column and were condensed in a decanter in the gas exit line. The bottom phase, consisting of para-xylene dissolved in propionic acid, was returned to the oxidation reactor.

After 20 hours, the process was stopped, the reaction medium was filtered, and there was obtained 56.8 grams of almost colourless terephthalic acid (97% pure), which corresponds to a molar pass yield of 90.6%.

Example 3

The proportions and procedural details were the same as in Example 2 except that the boil-up rate was decreased to 0.5 gram mole propionic acid per hour. 100 litres of propionic acid vapour (measured at 150° C.) was blown over the surface of the reaction medium at 150° C. in order to maintain the total composition of the vapour outside its upper inflammability limit.

After 20 hours the process was stopped and on filtration of the suspension there was obtained 56.7 grams of terephthalic acid (95.3% pure), which corresponds to a molar pass yield of 90.5%.

Example 4

40 grams of ortho-xylene dissolved in 200 grams of molten benzoic acid containing as catalyst 0.33 gram of MnBr₂.4H₂O

and 0.19 gram of CoBr₂.6H₂O together with 50 grams of benzene, was oxidised with a well dispersed stream of oxygen at 150° C. under atmospheric pressure using 12 litres per hour of oxygen. The boil-up rate of the liquid was maintained at about 300 ml. of liquid hydrocarbon per hour, and the composition of the vapour thus maintained above its upper inflammability limit. The hydrocarbon vapours from the reaction zone after passage through a packed reflux column were condensed in a decanter in the gas exit line, the lower aqueous phase was removed from the system, and the hydrocarbon was recycled to the oxidation reactor.

After running for 20 hours, 27 mls. of water was added to the mixture, and the whole was hydrolysed under total reflux for 2 hours. On filtration of the molten reaction medium there was obtained crude ortho-phthalic acid, which, after purification by boiling with ortho-xylene, yielded on drying, 9.3 grams of substantially pure acid.

The amount of ortho-xylene in the filtrate was again made up to 40 grams and the process was repeated. This was repeated another four times, and there was obtained in all 258.5 grams of ortho-phthalic acid (98.3% pure). 22 grams of ortho-xylene was recovered from the cold trap, and therefore the overall yield was 91.2% molar.

Example 5

The proportions of the reactants and the procedural details were the same as in Example 4 except that the boil-up rate of the liquid was decreased to 50 mls. of hydrocarbon per hour. 50 litres per hour of industrial nitrogen measured at 20° C. was blown over the reaction surface, whereby the upper inflammability limit was lowered, so that under these conditions the vapour over the liquid was non-inflammable.

After 20 hours the process was stopped and following treatment in a manner similar to that described in Example 4, 13.2 grams of phthalic acid was obtained for one pass.

Example 6

For this run 40 grams of ortho-xylene and 0.5 gram of CoBr₂.6H₂O were added to the filtrate obtained after filtering off the phthalic acid from the product obtained in Example 5. The other procedural details were the same, except that carbon dioxide at a rate of 50 litres per hour, measured at 20° C., was passed over the surface of the liquid.

After 20 hours, the process was stopped, the product was hydrolysed by adding 18 mls. of water and refluxing for 1½ hours, and the ortho-phthalic acid precipitated was filtered off. 50.8 grams of substantially pure ortho-phthalic acid were obtained.

We claim:

- 20 1. In processes for the production of benzene carboxylic acids by oxidation in the liquid phase at elevated temperatures with gaseous oxygen of the alkyl side-chains of alkyl-substituted benzene hydrocarbons in the presence of a catalyst selected from the group consisting of cobalt bromide and manganese bromide and wherein there is present above said liquid phase a vapor phase containing hydrocarbon and oxygen, the improvement which consists essentially of the combination of steps of:
  - (1) incorporating a hydrocarbon solvent in said liquid phase, relatively more volatile than any of the other components of said phase; and,
  - (2) maintaining a boil-up rate such that the vapor of said solvent maintains the hydrocarbon composition of the vapor phase over said liquid phase above the upper explosive limit thereof.
- 25 2. The process of claim 1 wherein said solvent is selected from the group consisting of volatile benzene hydrocarbons, lower aliphatic acids, halogenated benzenes, and fully halogenated aliphatic hydrocarbons.
- 30 3. In processes for the production of benzene carboxylic acids by oxidation in the liquid phase at elevated temperatures with gaseous oxygen of the alkyl side-chains of alkyl-substituted benzene hydrocarbons in the presence of a catalyst selected from the group consisting of cobalt bromide and manganese bromide and wherein there is present above said liquid phase a vapor phase containing hydrocarbon and oxygen, the improvement which consists essentially of the combination of steps of:
  - (1) employing a boil-up rate no more than normal for said liquid phase; while,
  - (2) introducing vapors of a volatile organic liquid into the vapor phase over the surface of said liquid phase so that the hydrocarbon composition of the vapor phase is maintained above its upper explosive limit.
- 35 4. The process of claim 3 wherein said volatile organic liquid is selected from the group consisting of volatile benzene hydrocarbons, lower aliphatic acids, halogenated benzenes, and fully halogenated aliphatic hydrocarbons.
